UNITED STATES PATENT OFFICE.

JOHN C. ROBBINS, OF WALTHAM, MASSACHUSETTS.

DESIGN FOR A BICYCLE CLUTCH MEMBER.

SPECIFICATION forming part of Design No. 30,539, dated April 11, 1899.

Application filed March 17, 1899. Serial No. 709,556. Term of patent 7 years.

To all whom it may concern:

Be it known that I, JOHN CHARLES ROB-
BINS, of Waltham, in the county of Middlesex
and State of Massachusetts, have invented and
5 produced a new and original Design for Bicy-
cle Clutch Members, of which the following is
a specification, reference being had to the ac-
companying drawings, forming part thereof.

In the drawings, Figure 1 represents a per-
10 spective view of a bicycle clutch member,
illustrating my new design. Fig. 2 represents
an end view thereof, and Fig. 3 represents a
longitudinal sectional view of the same.

The leading feature of my new design for
15 bicycle clutch members consists in the design
as herein shown and described.

As shown in the drawings, on the exterior
the clutch member has the contracted tubu-
lar portion 5 enlarged by the annular shoul-

der 6 to the surface 7 extending to the dia- 20
metrically-enlarged circular portion 8, in the
periphery of which are the pockets 9 9, gen-
erally concaved in cross-section and curving
outward from the radial faces 10 10 to the pe-
ripheral face of this portion 8. On the inter- 25
rior the clutch member has the inwardly-con-
tracted portion 11 with the opening 12, the
face 13 of this contracted portion being con-
nected with the annular surface 14 by the
slightly-curved shoulder 15. 30

What I claim is—

The design for a bicycle clutch member as
herein shown and described.

JOHN C. ROBBINS.
